ELECTRIC IRON

Taylor Cole, Midland, Tex., assignor to Cherie Cole, Austin, Tex.

Application September 28, 1937, Serial No. 166,153
Renewed May 19, 1939

3 Claims. (Cl. 177—311)

The invention relates to electrically heated irons and it aims to provide an improved article having a handle which is pervious to light, and a bulb in said handle for emitting light rays therethrough whenever current is being supplied to the heating element of the iron. The handle is thus conspicuously illuminated whenever the current is on, obviating all guessing and lessening the probability of dangerous over-heating.

With the foregoing in view, the invention resides in the novel subject matter hereinafter described and claimed, description being accomplished by reference to the accompanying drawing.

Fig. 1 is a side elevation of an iron improved in accordance with the present invention.

Fig. 2 is an enlarged side elevation partly broken away and in section.

Fig. 3 is a fragmentary rear elevation.

Fig. 4 is a front elevation of the cap plate which is secured to the rear end of the handle.

Fig. 5 is a diagram showing the manner of conducting current simultaneously to the handle illuminating bulb and the heating element of the iron.

Preferred details of construction have been illustrated and will be rather specifically described, with the understanding however, that within the scope of the invention as claimed, variations may be made.

An electric flat-iron is shown having a body 6 provided with the usual sole plate 7, with a conventional heating element 8, and with the customary contacts 9 conductively connected at

10 with said heating element, said contacts being engageable with the usual connection 11 on the current supply cord 12.

Front and rear handle brackets 13 and 14 are suitably secured to and project upwardly from the body 6, and a handle 15 extends between the upper ends of said brackets, said handle being formed from glass, Celluloid or any other desired transparent or translucent material, either colored or clear. This light-pervious handle 15 is provided with a longitudinal cavity 16 in which an illuminating bulb 17 is mounted, said bulb being preferably a small neon tube. Wiring 18 conductively connects the bulb 17 with the contacts 9, insuring that said bulb shall be illuminated whenever current is being supplied to the heating element 8, the light rays emitted through the light-pervious handle 15, serving to conspicuously illuminate the latter whenever the current is on.

55 A cap plate 19 is secured against the rear end

of the handle 15 by screws or the like 20 and closes the rear end of the cavity 16, and said cap plate 19 is secured to the rear bracket 14 by a screw 21. Another screw 22 secures the front end of the handle 15 to the bracket 13. The lower portion of the cap plate 19 is formed with a recess 23 extending from its front side through its lower edge, and the upper end of a conduit 24 for the wiring 18, is held within the lower end of said recess 23, the lower end of said conduit 24 being disposed within a suitable opening 25 in the upper portion of the body 6. Where the wiring 18 leaves the upper end of the conduit 24, it passes through the upper portion of the recess 23 into the rear end of the cavity 16, and one wall of this cavity may if required be provided with a groove 26 to accommodate said wiring.

It will be seen from the foregoing that I have provided a new and improved iron, the handle 20 of which is conspicuously illuminated whenever the current is on, eliminating all guess-work and reducing the probability of over-heating with accompanying dangers. While I am aware that the broad idea of a tell-tale light to indicate 25 when the current is on, is old, I believe a handle pervious to light and a bulb within this handle for emitting rays therethrough when the current is on, is original with me.

While the desired result may be obtained with 30 the details disclosed, attention is again invited to the possibility of making variations within the scope of the invention as claimed.

I claim:

1. An electric flat-iron comprising a body provided with a heating element and contacts connected therewith, front and rear handle brackets projecting upwardly from said body, a handle pervious to light and extending between said brackets, means securing said handle to said brackets and leaving the major central longitudinal portion of said handle unoccupied by any portion of said securing means, said major central longitudinal portion of said handle being provided with a longitudinal cavity, an elongated handle-illuminating bulb mounted in said cavity, and conductors for said bulb operatively connected with said bulb and said contacts.

2. An electric flat-iron comprising a body provided with a heating element and contacts connected therewith, front and rear handle brackets projecting upwardly from said body, a handle extending between the upper ends of said brackets, said handle being pervious to light and having a longitudinal cavity which opens through its rear

55

end, a cap plate abutting said rear end of said handle and closing the rear end of said cavity, said cap plate having a recess from its front side to its lower edge, a conduit at the front side of said rear bracket, said conduit extending upwardly from said body into the lower end of said recess, means securing the front end of said handle to said front bracket, screws spaced around said cavity, said screws passing through said cap plate and being threaded into said handle to secure the cap plate and handle together, a screw passing through said rear bracket and threaded into said cap plate to secure said cap plate and rear bracket together, a bulb in said cavity, and conductors for said bulb conductively connected with said bulb and said contacts and passing through said conduit.

3. An electric flat-iron comprising a body provided with a heating element and contacts connected therewith, front and rear handle brack-

ets projecting upwardly from said body, a handle extending between the upper ends of said brackets, said handle being pervious to light and having a longitudinal cavity which opens through its rear end, a cap plate abutting said rear end of said handle and closing the rear end of said cavity, said cap plate having a recess from its front side to its lower edge, a conduit at the front side of said rear bracket, said conduit extending upwardly from said body into the lower end of said recess, means securing the front end of said handle to said front bracket, means securing said cap plate to said rear end of said handle, means securing said cap plate to said rear bracket, a bulb in said cavity, and conductors for said bulb conductively connected with said bulb and said contacts and passing through said conduit.
